REFRIGERATOR

Alfred E. Nave, Newburgh, Ind., assignor to Servel, Inc., New York, N. Y., a corporation of Delaware

Application July 10, 1940, Serial No. 344,709

1 Claim. (Cl. 20—74)

This invention relates to refrigerator cabinet wall structure having spaced metal panels connected by insulating strips and it is an object of the invention to provide a trim or breaker strip shaped so as to be made by extrusion molding of a thermally insulating, non-hygroscopic plastic, and which is shaped to resist warping and provide concealed fastening means as set forth in the following description and accompanying drawing, of which:

Fig. 1 is a perspective of a household refrigerator cabinet embodying the invention;

Fig. 2 is an enlarged detail section on line 2—2 of Fig. 1;

Fig. 3 is a fragmentary perspective of the trim strip shown in Fig. 2;

Fig. 4 is a perspective of the spring clip forming part of the fastening means in the structure of Fig. 2;

Fig. 5 is a transverse section of the trim strip 20 of Fig. 2, showing the spring clip of Fig. 4 attached to said strip prior to the assembling of the strip in position on the refrigerator cabinet; and

Figs. 6, 7, 8, 9 and 10 are views similar to that of Fig. 2 showing modifications also embodying 25 the invention.

Like reference characters denote like parts in the several figures of the drawing.

In Fig. 1, a refrigerator 10 of the household type comprises a cabinet 11 having a doorway 12 and a door 13. Referring to Figs. 1 to 5, the cabinet 11 comprises an outer metal panel 15 and an inner metal liner 16 separated by suitable insulation 17. The outer panel 15 has a section 18 bent inward substantially at right angles to the main body section 19 thereof to form the front face of the cabinet 11 bordering the doorway 12, and terminates in an inturned rim flange 21 serving as a shoulder for a trim strip 22 as will be more fully described. The inner liner 16 has a curved section 23 also forming a shoulder for the trim strip 22. Adjoining this shoulder 23 is an outward rim flange 24 extending substantially parallel to the main flat body section 25 of said inner liner.

Between the spaced panels 15 and 16 adjacent the rim flanges 21 and 24 thereof is a spacing member 26 to which the panels are attached by suitable means as for instance nails 27.

Mounted between the panels 15 and 16 are the 50 breaker or trim strips 22, made from suitable insulating, non-hygroscopic plastic material such as hard rubber or synthetic resin, each having a uniform cross-section throughout its length so that it can be made by the process of extruding 55

the plastic material through a die. Four of these extruded plastic strips are shown framed around the doorway 12 and interconnected by suitable corner pieces 28 to complete the doorway frame.

5 Each trim strip 22 is supported against the outer panel rim flange section 21 and the inner liner curved section 23 by means of a series of spaced concealed fastening elements in the form of spring clips 29. To receive the spring clips 29, 10 each trim strip 22 is provided on its inner face with a pair of spaced symmetrically arranged ribs or ridges 30 having respective recesses or rabbets 31 on their outer facing corners to receive the ends of the spring clips 29 as will be more fully described. Centrally between the two ribs 30 is a third rib 32 which has a depth less than that of the two side ribs 30 and which serves as a stop or backing support for the spring clips 29 in strip mounted position.

Each spring clip 29 comprises a spring metal plate of substantially rectangular shape having serrated edges 33 for firm engagement in the rabbets 31. A nail prong 34, cut or stamped out from the main body of the clip 29, is bent out of the plane thereof and is pointed at its outer end for drive entry into the wooden spacer 26.

The spring clip 29 is preformed with a slight convex curvature with respect to its nail prong 34 as shown in Figs. 4 and 5, and is of a size to permit insertion thereof between the two ribs 30 with its serrated edges 33 in the rabbets 31 as shown in Fig. 5 prior to the mounting of the trim strip 22 in position. If desired, the spring clip 29 may be formed flat and bowed into strip gripping position shown in Fig. 5. With either form of construction, a series of spring clips 29 are first attached to the trim strip 22 in spaced relationship therewith and the body of these clips bowed away from the inner face of said strip. When the clips 29 have been so attached, the strip 22 is applied in the approximate position shown in Fig. 2 between the two panels 15 and 16, and said strip hammered towards the member 26. 40 This operation drives the nail prongs 34 into the frame 26 and at the same time snaps the clips 29 into slightly reverse curvature so they abut the center rib 32 as shown in Fig. 2. The center rib 32 is deep enough to prevent full reversal of curvature of the spring clips 29 from their original positions shown in Fig. 5 so that the serrated edges 33 of said clips dig firmly into engagement with the side ribs 30. With the clips 29 snapped into reverse curvature, continued hammering of the trim strip 22 will drive the nail prongs 34 into

the wooden frame 26 until the trim strip 22 abuts the shoulder sections 21 and 23.

In order to provide clearance for the side ribs 30 in mounted position of the strip 22, the frame 26 has a suitable recess 35. The ribs 30 and 32 serve not only as a means for supporting the spring clips 29, but also serve as reinforcing members to prevent warpage of the strip.

In the construction shown in Fig. 6, the extruded plastic trim strip 22a has integral with its inner face a central rib 40 of substantial width for holding a series of metallic fastening elements 41 in spaced relationship therewith. Each of these fastening elements 41 comprises a screw section 42 having its threads steep enough to permit said section to be hammer driven into the rib 40, a nail section 45 adapted to be driven into the wooden frame 26, and a collar 46 separating the two drive sections 42 and 45 and serving as a shoulder for engagement with the inner face of the rib 40. In order not to damage the point of each of the nail sections 45 during this drive operation, the drive screw section 42 may be driven into the rib 40 by hammering a sleeve encircling the nail section 45 and abutting the collar 46.

After the fastening elements 41 have been attached to the strip 22a as described, the strip is secured in position between the panels 15 and 16 by hammering said strip to drive the nail sections 45 of said elements into the frame 26 until the trim strip 22a abuts the shoulder panel sections 21 and 23.

In the construction shown in Fig. 7, the extruded plastic trim strip 22b has integral with its inner face a rib 50 to which is attached a series of metallic fastening elements 51 spaced therewith. Each of these fastening elements is in the form of a clip made of spring plate having a substantially flat section 52 secured to the inner face of the rib 50 by suitable means shown in the form of a screw 53. One side marginal section 54 of this clip extends beyond the rib 50, while the other side marginal section 55 also extends beyond said rib and terminates in an outwardly inclined flange 56. In order to latch the sides of the spring clips 51 in position, the rim flange 21b of the outer panel 15 extends inward beyond the adjacent side of the recess 35b, while the rim flange 24b of the inner liner 16 extends outward beyond the adjacent side of said recess.

In assembling the trim strip 22b, a series of spring clips 51 are first attached in spaced relationship along the rib 50. The clip flanges 56 are then slipped under the inner side of the rim flange 24b, and the trim strip 22b pressed towards said rim flange. During this operation, the clip flanges 56 abutting the edge of the rim flange 24b are flexed until the edges of the marginal clip sections 54 clear the edge of the rim flange 21b. In this position, the trim strip 22b is moved inward to bring the marginal clip sections 54 to the inner side of the rim flange 21b. The spring clips 51 under the spring action of their flanges 56 will snap into latch engagement with the rim flanges 21b and 24b with the sides of the strip 22b supported against the shoulder sections of the panels 15 and 16.

In the construction shown in Fig. 8, the extruded plastic trim strip 22c has integral with its inner face a rib 60 of step-like formation with its side 61 extending at an angle with respect to the general plane of said strip, and its inner face 62 extending substantially at right angles to said side and substantially horizontal in oblique mounted position of the trim strip 22c.

Attached to the rib 60 is a series of metallic fastening elements 63 in the form of spring clips, each kinked to define adjoining angular sections 64 and 65, one of said sections 65 terminating in an inward flange 66, while the other section 64 is secured to the rib 60 by suitable means shown in the form of a screw 67, and extends at its marginal edge beyond said rib.

In order to latch the spring clips 63 in position, the rim flange 21c of the outer panel 15 extends inward beyond the adjacent side of the recess 35c in the face of the frame 26c, while the rim flange 24c of the inner liner 16 extends outwardly beyond the adjacent side of said recess.

In assembling the trim strip 22c, a series of spring clips 63 are first attached in spaced relationship along the rib 60. The flanges 66 of these spring clips 63 are slipped over to the inner side of the rim flange 21c, and the strip 22c pressed towards said rim flange. During this operation, the clip sections 65 abutting the edge of the rim flange 21c are flexed until the marginal edges of said clip sections 64 clear the edge of the rim flange 24c. In this position, the trim strip 22c is moved inward to bring the marginal edges of the clip sections 64 to the inner side of the rim flange 24c. The spring clips 63 under the spring action of their sections 65 snap into latch engagement with the rim flanges 21c and 24c as shown, with the side sections of the trim strip 22c supported against the shoulder sections of the panels 15 and 16.

In the construction shown in Fig. 9 the liner 16 has its edge terminating in a rim flange 71 forming the outer side of the bulge or bead section 23d on said liner. The wooden frame 26d has a section 72 abutting the rim flange 71 and secured thereto by any suitable means as for instance by the nails 73.

The extruded plastic trim strip 22d has a pair of parallel ribs 74 formed with outward extending ledges 75 serving as catches for latch engagement of metallic fastening elements 76. Each of these fastening elements 76 is in the form of a U-shaped spring clip having a flat base section 77 abutting the base of the recess 35d formed in the outer face of the frame 26d and secured thereto by any suitable means as for instance nails 78. The side arms of each spring clip 76 have inturned curved latch sections 79.

For assembling operation, a series of clips 76 are secured to the frame bar 26d in spaced relationship along the recess 35d, and the trim strip 22d is secured in position by merely pushing said strip inward towards the shoulder sections of the panels 15 and 16. During this assembling operation, the latch sections 79 of the spring arms are first pressed outward as they ride over the edges of the ledges 75, and then are snapped over said ledges after they clear said ledges.

In the construction shown in Fig. 10, the extruded plastic trim strip 22e has formed integral with its inner face a comparatively wide rib 80 provided with a central recess 81. A series of spaced plates 82 abut the face of the rib 80. Each of these plates 82 has a central section offset into the recess 81 and secured to said rib by suitable means as for instance a screw 83, and side sections 84 extending beyond the corresponding sides of the rib 80. U-shaped spring clips 85, similar to the clips 76 shown in the construction of Fig. 9, and similarly fixed to the frame 26e, are disposed opposite respective plates 82. Each of these clips 85 is provided with side arms 86 converging away from the base section thereof

and presenting inwardly curved sections 87 for riding engagement over the edges of a respective plate 82. These side arms 86 are latched over the projecting sides 84 of the plate 82 when the strips 22e with a series of plates 82 attached thereto are pressed towards the spring clips 85.

Although the recess 81 in the rib 80 is not necessary, it is desirable in order that the heads of the screws 83 do not interfere with the mounting of the strip 22e in proper position.

In all of the constructions shown, the trim strip is made of extruded plastic material and is therefore of uniform cross-section throughout its length. This strip is formed with one or more ribs cooperating with metallic fastening elements for attachment of said strip between the panels of the refrigerator cabinet. These metallic fastening elements are entirely concealed by the trim strip, so that the ornamental appearance of the strip is enhanced. The rib or ribs on the inner face of the trim strip serve not only as a means for attachment of the fas-

tening elements, but also serve to impart substantial rigidity to the strips against their tendency to warp.

Various changes may be made within the scope 5 of the invention as set forth in the following claim.

I claim:

A trim strip for use on a refrigerator cabinet wall, said strip being substantially flat and having 10 a pair of substantially parallel spaced ribs on one face thereof, a third rib located between said pair of parallel ribs and being of lesser height than the height of said parallel ribs, and a substantially rectangular bowed fastening strip 15 having a pointed prong substantially normal to the convex face thereof, said fastening strip being positioned in the channel between said parallel ribs so that the fastening strip when flattened is wedged between said parallel ribs with the portion of said fastening strip opposite said prong bearing against said third rib.

ALFRED E. NAVÉ.
